Primary Examiner—M. N. Pandozzi**Attorney, Agent, or Firm**—William C. Crutcher**[57]****CLAIM**

The ornamental design for a “squeeze bottle for filtering and purifying drinking water”, as shown and described.

DESCRIPTION

FIG. 1 is a perspective view of our improved squeeze bottle for filtering and purifying drinking water;
 FIG. 2 is a left side elevational view with a removable cap hanging to the left side thereof;
 FIG. 3 is a right side elevational view thereof;
 FIG. 4 is a rear elevational view thereof;
 FIG. 5 is a front elevational view thereof;
 FIG. 6 is a top plan view thereof;
 FIG. 7 is a bottom plan view thereof; and,
 FIG. 8 is a left side elevational view as in FIG. 2, but with the cap in closed position.
